UNITED STATES PATENT OFFICE.

DAVID F. DOUGHERTY, OF BUTLER, PENNSYLVANIA.

DESIGN FOR AN ENVELOP-BLANK.

SPECIFICATION forming part of Design No. 35,416, dated December 10, 1901.

Application filed October 26, 1901. Serial No. 80,153. Term of patent 7 years.

To all whom it may concern:

Be it known that I, DAVID F. DOUGHERTY, a citizen of the United States of America, residing at Butler, in the county of Butler and State of Pennsylvania, have invented and produced a certain new and original Design for Envelop-Blanks, of which the following is a specification, reference being had therein to the accompanying drawing.

The invention relates to a new and original design for an envelop-blank; and it consists of a blank of the shape and configuration shown in the accompanying drawing, in which I have illustrated the invention in plan view.

The leading feature of the design consists of the rectangular body portion 1 and end flaps 2, the lower edges of which are on a horizontal line with the lower edge of the body portion and the upper edges of which have a tapering curve 3. The rear flap 4 joins

with the lower edges of the body 1 and has its free edge of the same length as the body portion, the ends 5 curved inwardly and the edge 6 also having an inward curve with a slit 7 near the outer edge. The flap 8 joins with the upper edge of the body portion 1 and has both of its edges curved, this curved line meeting with the curved edge 3 of the flaps 2 and imparting a wavy appearance to this edge of the blank.

What I claim as new, and desire to secure by Letters Patent, is—

The design for an envelop-blank, as herein shown and described.

In testimony whereof I affix my signature in the presence of two witnesses.

DAVID F. DOUGHERTY.
